UNITED STATES PATENT OFFICE.

SMITH BEERS, OF DANBURY, CONNECTICUT.

WHIFFLETREE-COUPING.

SPECIFICATION forming part of Letters Patent No. 394,811, dated December 18, 1888.

Application filed May 22, 1888. Serial No. 274,693. (No model.)

To all whom it may concern:

Be it known that I, SMITH BEERS, a citizen of the United States, residing at Danbury, in the county of Fairfield and State of Connecticut, have invented certain new and useful Improvements in Whiffletree-Couplings; and I do hereby declare the following to be a full, clear, and exact description of the invention, such as will enable others skilled in the art to which it appertains to make and use the same.

My invention has for its object to provide a device of this class adapted either to attach a whiffletree to a cross-bar or an evener to a pole, the essential requirements being that the device shall be simple in construction, strong, neat in appearance, and inexpensive to produce, and the special advantages of my improved construction being, first, that I provide a double connection between the whiffletree and the cross-bar, so that if the ordinary whiffletree-bolt breaks the whiffletree still remains firmly attached to the cross-bar, and, secondly, that I limit the oscillation of the whiffletree or evener, thereby preventing contact with the wheels and rendering the use of straps unnecessary.

With these ends in view I have devised the novel construction of which the following description, in connection with the accompanying drawings, is a specification, numbers being used to denote the several parts.

Figure 1 is an elevation of a portion of a cross-bar and whiffletree, showing my improved coupling in use. Figs. 2 and 3 are respectively inverted plan and edge views of the whiffletree-plate detached; Fig. 4, a plan view of the upper plate; and Fig. 5 is a plan view of the lower plate for attachment to the cross-bar.

1 denotes the whiffletree, and 2 the cross-bar, or, in case two horses are to be used, the parts are respectively designated as "single-tree" and "evener" or "doubletree."

3 denotes a plate, which is secured to the whiffletree by bolts 4, and which is provided with a bearing-surface, 5, and a central stud, 6, having at its outer end a cross-piece, 7.

8 and 9 denote, respectively, upper and lower plates, attached to the cross-bar by bolts 10, passing through both plates. Plate 9 lies next to the cross-bar, and is provided

with a central opening, 11, the longest diameter of which lies transversely to the plate. The upper plate is provided with a central opening, 12, the longest diameter of which lies longitudinally to the plate, and with a bearing-surface, 13, corresponding with surface 5 upon plate 3, the two surfaces lying in contact in use.

14 denotes the ordinary whiffletree-bolt, which is passed through the usual openings in the whiffletree and cross-bar, through an opening, 15, made through plate 3, the stud and cross-piece, and through the central openings in plates 8 and 9.

In attaching, plate 3 is first secured to the whiffletree by bolts 4. Bolts 10 are then placed in the screw-holes in plate 8, the cross-bar is passed through the opening in said plate, after which the plate is turned parallel with plate 3, and then the bolts are passed through the holes in plate 9, and the cross-bar is placed in opening 11. Bolts 10 are then passed through the usual openings in the cross-bar and secured by nuts in the usual manner, after which the whiffletree-bolt is passed through all of the plates, the whiffletree, and the cross-bar, and secured by a nut in the usual manner.

The operation of the cross-piece in opening 11 in plate 9 is clearly shown in Fig. 5. The exact shape of the opening or of the cross-piece is not an essential feature of my invention. I make the cross-piece slightly smaller than the opening, and ordinarily taper the sides slightly, as shown, so as to permit sufficient movement of the cross-piece in the opening to give the desired amount of oscillation to the whiffletree, such oscillation being limited by the contact of the edges of the cross-piece with the sides of opening 11. It will be seen that after plates 8 and 9 are attached to the cross-bar by bolts 10 the whiffletree is held in place very strongly, irrespective of the ordinary whiffletree-bolt, which I have designated by 14, so that should said bolt break in use there will be no danger whatever of the whiffletree dropping, as it will be firmly held by the stud and cross-bar, which will be in engagement with the openings in plates 8 and 9, the cross-piece lying transversely to the opening in plate 8, so that it cannot be removed until the whiffletree-bolt and bolts

10 have been taken out, the parts all lifted from the cross-bar, and plate 9 dropped. The whiffletree may then be turned at a right angle to plate 8, which will place the cross-piece 5 at the lower end of the stud in line with opening 12 in plate 8, when said plate may be detached.

It will of course be understood that the various details of construction may be changed 10 within reasonable limits without departing from the spirit of my invention.

I claim—

1. A whiffletree-coupling consisting of a plate for attachment to the whiffletree, provided with a stud and a cross-piece, and lower plates for attachment to the cross-bar, said plates having central openings lying transversely to each other, the opening in the lower plate being adapted to receive the cross-piece 20 when the whiffletree is in operative position, and to limit the oscillation thereof by the engagement of the cross-piece with the sides of the opening.

2. A whiffletree-coupling consisting of a plate for attachment to the whiffletree, having a bearing-surface, 5, a central stud, and a cross-piece at the outer end thereof, and upper and lower plates for attachment to the cross-bar having openings to receive the cross-piece lying transversely to each other, the upper plate having a bearing-surface corresponding with surface 5.

3. Plate 3, having a stud and a cross-piece, with a hole, 15, through said plate, stud, and cross-piece, and plates 8 and 9, having openings 12 and 11 lying transversely to each

other, in combination with the cross-bar and whiffletree and bolt 14, passing through the whiffletree and cross-bar and through said plates, the stud, and the cross-piece, substantially as described. 40

4. A whiffletree, plate 3, having a central stud and cross-piece, and bolts securing said plate to the whiffletree, in combination with a cross-bar, upper plate, 8, having a central 45 opening lying transversely to the cross-piece, a lower plate, 9, having an opening to receive the cross-piece when the whiffletree is in operative position, and bolts passing through plates 8 and 9 and the cross-bar, whereby all 50 of the parts are retained in operative position.

5. The combination, with the whiffletree, plate 3, having a bearing-surface, a central stud, and a cross-piece, with an opening 55 through said plate, stud, and cross-piece, and bolts securing said plate and the whiffletree, of the cross-bar, plate 8, having a bearing-surface and an opening to receive the cross-piece, but lying transversely thereto in its 60 normal position, plate 9, having an opening to receive the cross-piece in its normal position, bolts securing said plate to the cross-bar, and a bolt, 14, extending through the whiffletree and cross-bar and all of the parts 65 of the coupling.

In testimony whereof I affix my signature in presence of two witnesses.

SMITH BEERS.
